UNITED STATES PATENT OFFICE.

FRANK A. HOWARD, OF ELIZABETH, NEW JERSEY, ASSIGNOR TO STANDARD OIL DEVELOPMENT COMPANY, A CORPORATION OF DELAWARE.

PROCESS OF CONVERTING HYDROCARBONS INTO LOWER-BOILING PRODUCTS.

Application filed May 21, 1923. Serial No. 640,491.

This invention relates to the art of pyrolytic conversion of hydrocarbons to lower boiling products and will be fully understood from the following description, reference being had also to the accompanying drawing which represents diagrammatically one form of apparatus by which the invention may be practiced.

In the drawing, the reference character A designates a heated conduit or passageway of suitable construction, for example a bank of tubes connected at the ends by cross-over connections from tube to tube and row to row to allow flow of fluid in a consecutive path and arranged to be heated, as for example by a furnace. Connected to the first passageway by a pipe 1 is a further passageway, which may be constructed along similar lines or as an enlarged passageway or drum B as more particularly illustrated, and in any case guarded against heat loss, as by being covered with insulation or mounted so as to be bathed by hot gases, as preferred. From the passageway B a connection 2 preferably having a pressure-release valve 3, leads to a vapor separator C, and a vapor line 4 from thence passes to suitable condensing means. A tar draw-off 5 is provided at the bottom of the vapor separator and a lateral line 6 for heavy condensate where such is collected from the vapors rising in the vapor separator.

A pipe 7 from a source of oil supply 8 connects into the heating conduit A, and a pipe 9 from a source of supply 10 connects into the passageway B, and either or both of the lines as desired may be connected through heat exchangers for preliminary heating of the stocks; conveniently for instance, heat exchangers on the vapors disengaged at the vapor separator being employed.

Oil is fed from the source of supply 8 into the heating conduit or coil A, and it is preferable here to feed a relatively "clean" oil, that is, an oil which will completely vaporize with a minimum formation of carbon. Such an oil may be for instance a kerosene or a light gas oil, and with such a very high coil outlet temperature, for example around 900-1000° F. may be employed. Through the pipe 9 the passageway B may be fed also with a relatively "dirty" stock, or stock of relatively greater coke-forming tendencies; for example a crude residuum, high in asphaltic bodies or wax or both, or a heavy

distillate may be used, such as paraffine slop or heavy gas oil. An advantageous combination is light gas oil in the heating zone A with heavy gas oil introduced into the second zone B.

In such manner the heating zone A may be operated relatively cleanly and heat carried by the products passing on to the next zone B may there aid in the conversion under pressure of additional amounts of hydrocarbons of different character as desired, and particularly residuum or heavy distillate stocks having considerable coke-forming tendency.

While I prefer to operate the heating zone so as to secure a considerable portion of the cracking therein the hydrocarbons being also substantially completely in vaporous condition, and then finish in the second zone using the heat already acquired to also crack additionally introduced stocks of different character, in its broader aspects my invention also contemplates operating while adding the different stock in the second zone, irrespective of how much or how little the hydrocarbons may be in vaporous condition and irrespective of how the cracking is divided between the two zones.

What I claim is:

1. A process for the conversion of hydrocarbons into lower boiling products which comprises feeding a stream of light gas oil into a heating passageway at a temperature around 900-1000° F., to effect a material amount of cracking in vaporous condition, then passing the products into a further passageway which is guarded against heat loss, while also introducing a heavy gas oil, contacting said vapor and liquid products together for a substantial period of time and allowing conversion substantially in the liquid phase, to go on in the mixture solely on the heat already acquired, and passing the liquid products together with any vapors, from a point substantially above the bottom of the passageway guarded against heat loss into a vapor-separating zone and separating the lighter hydrocarbons from the heavier.

2. A process for the conversion of hydrocarbons into lower boiling products, which comprises passing a stream of hydrocarbons of substantially completely vaporized character through a heating passageway at a temperature around 900-1000° F. to effect a material amount of cracking in vaporous condition, then passing the products into a further

passageway which is guarded against heat loss, while also introducing a hydrocarbon stock having greater coke-forming tendency, contacting said vapor and liquid products together for a substantial period of time allowing conversion substantially in the liquid phase to go on in the mixture solely on the

heat already acquired, and passing the liquid products, together with any vapors, from a point substantially above the bottom of the passageway guarded against heat loss into a vapor-separating zone and separating the lighter hydrocarbons from the heavier.

FRANK A. HOWARD.
